United States Patent Office.

EDWARD WIARD, OF LOUISVILLE, KENTUCKY, ASSIGNOR TO HIM
SELF AND SAMUEL W. POPE, OF SAME PLACE.

Letters Patent No. 85,152, dated December 22, 1868.

IMPROVEMENT IN PLOWS.

The Schedule referred to in these Letters Patent and making part of the same.

To all whom it may concern:

Be it known that I, EDWARD WIARD, of Louisville, in the county of Jefferson, and State of Kentucky, have invented a new and useful Improvement in Plows; and I do hereby declare that the following is a full, clear, and exact description thereof, which will enable others skilled in the art to make and use the same, reference being had to the accompanying drawings, forming part of this specification, in which—

Figure 1 is a detail cross-section, through the line x x , fig. 2.

Figure 2 is a view of the inside of a mould-board, showing the handle affixed thereto by means of my improved devices.

Similar letters of reference indicate like parts.

The object of this invention is to provide a simple and effective means of attaching the straight handle of plows to the mould-board; and

It consists of two peculiar-shaped seats, and one or more hooks cast on the inner side of the mould-board, in combination with a bolt or bolts passing through the handle, the whole operating together as herein set forth.

In the drawings—

A is the mould-board, and

a a , the two seats.

b is the hook, and

c , the bolt.

The seats are formed with side projections, which hold the handle B in place.

The hook or hooks b are formed with a slot, d , in which the bolt c is inserted.

The bolt has a head, f , and a nut, e , and serves to hold the handle tightly in its seats.

That portion of the bolt within the slot is made square, so that it cannot turn when the nut is being screwed or unscrewed.

The seats may be cast with small sharp projections, which will indent the encountering face of the wooden handle, and thus serve to prevent it from straining the bolt and hook, and enabling the bolt to hold the handle more firmly.

The seats and hook are cast on the mould-board, the hooks being arranged between the seats, as shown.

Having thus described my invention,

I claim as new, and desire to secure by Letters Patent—

The lugs a a , with their projecting points, in combination with the slotted hook or hooks b , the bolt c , handle B , and mould-board A , substantially as described, for the purpose specified.

EDWARD WIARD.
